EDUCATIONAL ART TEXT SHEET.

MY SYMPHONY.

To live content with small means;
To seek elegance rather than luxury, and refinement rather than fashion;
To be worthy, not respectable, and wealthy,
not rich;
To study and think quietly, talk gently, act
frankly;
To listen to stars and birds, to babies and
songs, with open heart;
To bear all cheerfully, do all bravely, await occasions, hurry never;
In a word, to let the spiritual, unbidden and unconscious, grow up through the common.
This is to be my symphony.

UNITED STATES PATENT OFFICE.

WILHELMINA SEEGMILLER, OF INDIANAPOLIS, INDIANA.

EDUCATIONAL ART TEXT-SHEET.

SPECIFICATION forming part of Letters Patent No. 720,187, dated February 10, 1903.

Application filed June 13, 1902. Serial No. 111,450. (No model.)

To all whom it may concern:

Be it known that I, WILHELMINA SEEGMILLER, a subject of the King of Great Britain, residing at Indianapolis, in the county of Marion and State of Indiana, have invented 5 certain new and useful Improvements in Educational Art Text-Sheets, of which the following is a specification.

At the present time considerable attention 10 is being paid in the public and other school systems to the training of the younger pupils to produce artistic effects with paints or crayons, and it is also found desirable to inculcate 15 lofty sentiments and standard quotations. It has been my experience that the pupil will retain a word-text more readily if the text is associated with something which is to be accomplished manually by the pupil.

The object of my present invention is therefore 20 to produce a sheet the face of which will carry a word-text and associate with this word-text an outline of an artistic ornamentation which is intended to be illuminated by the pupil by coloring-pigments of any desired kind, the 25 material of which the sheet is made being of a character adapted to readily receive and retain the illuminating-pigment and also of such character as to render it fit for permanent preservation if the pupil so desires. The 30 illumination also results in a development of the art sense of the pupil.

The accompanying drawing illustrates my invention, said drawing consisting of a word-text quotation from William Ellery Channing surrounded or partially surrounded by an outline border intended for illumination. 35

It will be readily understood that the particular word-text or the particular outline to be illuminated is not the essence of my invention, nor is the material of the sheet, so long 40 as it be of such character as to receive and retain the illuminating-pigment, my invention consisting instead of the association of a sheet of material adapted to receive and retain an illuminating-pigment, a word-text, 45 and an outline figure of a character to be illuminated.

I claim as my invention—

An education art text-sheet, consisting of a sheet of material adapted to receive and retain an illuminating-pigment, a literary extract carried upon the sheet, and an outlined ornamentation, intended to be illuminated, also carried on the sheet and embracing the extract. 50

In witness whereof I have hereunto set my hand and seal, at Indianapolis, Indiana, this 7th day of June, A. D. 1902.
